THOMAS WHALEY, OF ROCHESTER, NEW YORK.

STAMP-AFFIXING MACHINE.

1,209,919.

Specification of Letters Patent. Patented Dec. 26, 1916.

Application filed December 16, 1915. Serial No. 67,204.

To all whom it may concern:

Be it known that I, THOMAS WHALEY, of Rochester, in the county of Monroe, State of New York, have invented a new and useful Stamp-Affixing Machine, fully set forth in the following specification and shown in the accompanying drawings.

The present invention relates to stamp affixing machines and more particularly to the type in which the stamps are removed from a suitable magazine, moistened, and applied to the envelop or other mail matter, an object of this invention being to provide a construction which will be positive in its action, insuring the proper feeding and affixing of the stamps.

Another object of the invention is to provide a construction employing a magazine adapted to contain a number of rolls of stamps, preferably of different denominations, such magazine being shiftable to present anyone of the rolls to the feeding devices.

Still another object is to provide a feeding device for drawing the stamps from a stamp roll to a position where they may be engaged by a device to be carried to and affixed to an envelop.

A further object is to provide an affixing device having stamp-gripping means released when the stamp engages an envelop.

To these and other ends, the invention consists in certain parts and combinations of parts all of which will be hereinafter described, the novel features being pointed out in the appended claims.

In the drawings, Figure 1 is a side view of the machine with the cover removed and one of the stamp guides elevated; Fig. 2 is a view at right angles to that shown in Fig. 1 with the cover and parts of the water supply tank and the suction pump in section; Fig. 3 is a view of that side of the machine opposite that shown in Fig. 1, with the cover removed; Fig. 4 is a view of that side of the machine opposite that shown in Fig. 2, with the cover removed; Fig. 5 is a top view of the machine; Fig. 6 is a detail view showing the stamp-carrying and affixing device in the position which it assumes shortly prior to the affixing of the stamp, the operating mechanism of such affixing device also being shown; Fig. 7 is a view, partly in section, of the carrying and the affixing device while it is affixing the stamp; Fig. 8 is a view of the under side of the carrying and affixing de-

vice; Fig. 9 is a perspective view of the upper side of the carrying and affixing device; Fig. 10 is a detail view showing the carrying and affixing device removing the stamp from the receiving table; Fig. 11 is a detail sectional view of the stamp guide of the device for securing the shiftable magazine in different positions; Fig. 12 is a detail view of the devices for securing the stamp holder in different positions with relation to the table from which the stamps are removed by the carrying and affixing device; Fig. 13 is a detail view showing the operation of the carrier which carries the stamp from the stamp guide to the table, the carrier being shown in the position which it occupies when starting on its travel to secure the stamp; Fig. 14 is a section on the line *a—a*, Fig. 13; Fig. 15 shows a stamp carrier in the position it occupies when it grasps the stamp in the stamp guide; Fig. 16 is a section on the line *b—b*, Fig. 15; Fig. 17 is a detail view of the modification of the stamp magazine; Fig. 18 shows one of the stamp holders of Fig. 17 in side elevation, with the bearings of the magazine in vertical section; Figs. 19 and 20 are respective top and side views of a modification of the stamp affixer and carrier; Fig. 21 is a fragmentary elevation of the exterior casing, viewed from the right side of Fig. 1; and Fig. 22 is a perspective view of some of the parts shown in Figs. 21 and 12.

According to this invention, the stamps are mounted in the machine in any suitable manner. Preferably, a shiftable magazine is employed containing means for holding a plurality of rolls of stamps. This magazine may embody a frame consisting of a plurality of angularly formed frame pieces 1, connected together at one end by a strip 2, and at the other end by a rod 3. These frame pieces may be guided on a pair of rods 4 which are supported at their ends by standards 5 secured to a base plate 6. Between the frame pieces 1 are mounted swinging frames 7 formed by parallel arms connected at their inner ends to tubes 8 which turn on the upper rod 4 between the frame pieces 1. The outer ends of the arms of the swinging frames are each provided with laterally opening bearings 9 which receive the shafts 10 of the drum 11, on which the rolls of stamps are wound. Normally, the swinging frames 7 are pressed upwardly by springs 12 each secured at one end, at 13, to

a sleeve 8 and at the other end, at 14, to the strip 2.

In order that each stamp-holding drum may be held in feeding position, the magazine carries an arm 20 (see Figs. 12 and 22) on which is arranged a cylindrical guide 21 surrounded by a collar 22 having projections 23 for operating within a slot 24 formed in a casing cover 25. These projections 23 may be held in the slot by a coil spring 26 surrounding the cylindrical guide 21. A set screw 27 engages the outer end of the guide 21 and controls a locking plate 28, which has a projection 29 operating in the slot 24, and a projection 30 for engaging in any one of three openings 31 formed in the casing cover 25 for the purpose of locking the magazine in any one of three positions. In either of these positions, one strip of stamps is held in alignment with the receiving and affixing mechanism, and remains so until the set-screw 27 is loosened and the projection 30 on the locking plate 28 is disengaged from the opening 31, whereupon the frame pieces 1 and their associated parts may be moved along on the rods 4.

Mounted between the arms 1, to turn on the rod 3, are stamp guides 15 each having a slot 16 through which the stamps are threaded. Each guide has a pivoted frame 17 coöperating therewith and provided with a finger piece 18 by which it may be swung from the position shown in Fig. 11 to that shown in Fig. 1, a spring 19 acting on said pivoted frame 17 to hold it in the position shown in Fig. 11. The frame 17 embodies two spaced arms which engage the stamps near their opposite edges.

From the stamp guide, the stamps are fed preferably to a stamp receiving table 32 formed with a passageway 33 and supported by a standard 34 from the base plate 6, anyone of the stamp guides 15 being adapted to be alined with said stamp receiving table, 45 in the manner hereinbefore described. The preferred means for carrying the stamps from the stamp guide to the stamp receiving table embodies a carrier consisting preferably of two gripping members 35 and 36, the former of which is resilient and the latter of which is pivoted at 37 below the member 35 to a frame piece 38 from which the member 35 also projects. A spring 39 secured to the under side of the member 35 55 acts on the member 36 to move the latter away from the member 35. These gripping members are adapted to move through the slot of the stamp receiving table 33 to engage with one end of a stamp, located on that stamp guide 15 which is opposite the table 32, the stamp guide being provided with a slot 40 in which the members 35 and 36 are adapted to operate.

With the end in view of reciprocating the gripping devices or stamp carrier, the frame

38 of the latter may be guided on a rod 41 which projects horizontally from the standard 34. This frame 38 may also be provided with a ring 42 which is guided upon a drum 43 secured to a shaft 44, the latter being mounted in the standard 34 and a standard 45. The drum 43 is provided with a cam groove 46 in which a pin 47 operates, the pin being loosely mounted in the frame 38 so that it acts as an anti-friction device.

In order that the gripping devices will grip and release the stamp at the proper times, there may be provided an operator 48 pivotally mounted at 49 at its lower end to the standard 34 and having a roller 50 at 51 its upper end to coöperate with the under side of the pivoted gripping member 36. This pivoted operator 48 is engaged at 51 by a cam 52 secured to the shaft 44 to rotate with the latter and acting to move the gripping member toward the gripping member 35 as the gripping devices move toward the stamp guide to hold this gripping position while the stamp is being drawn to the receiving table 32, and to release the stamp when the parts assume the position shown in Fig. 15.

After the stamps have been received upon the receiving table 32, they may be severed from the strip by any suitable means, as a knife 53 pivoted at 54 at one side of the table and held away from cutting position by a spring 55, against the stop 56. This knife may be pressed by a projection 57 on a stamp-affixer and carrier which removes the stamp from the table and carries the same to the affixing position.

The stamp affixer and carrier preferably embodies a plate 58 carrying stamp holding means to be hereinafter described and having a central guide member 59 and side guides 60 which operate in a head 61 that is guided horizontally on a guide 62. The guide 62 is mounted for vertical movement and, to this end, is supported by tubular members 63 connected at their opposite ends by cross pieces 64 and 65. The tubular members operate on cylindrical guides 66 supported in parallel relation on the base piece 6, the cylindrical guides being surrounded by coil springs 67 which tend normally to hold the guide supporting frame in a raised position. The depression of this frame may be effected by any suitable means such, for instance, as cam arms 68 extending laterally from the shaft 44 and adapted to coöperate with a roller 69 journaled on a supporting plate 70 which is adjustably secured to the lower cross piece 65 of the guide supporting frame.

For the purpose of moving the head 61 on the guide 62, there is provided a mechanism comprising preferably a link 71 pivoted at 72 to the head and at 73 to a lever 74 which in turn is pivoted at 75 to a bracket 76 secured to the under side of the bed plate 6.

A link 77 is pivoted at 78 to the lever 74 and at 79 to the lever 80, the latter being pivoted at 81 to a bracket 82 on the under side of the bed plate 6, the levers 74 and 80 being parallel. On the link 80, a roller 83 is arranged to operate in a cam groove 84 formed in the face of a wheel or disk 85 that is mounted on the shaft 44.

For the purpose of holding the stamps to the plate 58, the latter may carry two grippers in the form of slides 86, guided on the upper surface of the plate 58, turned downwardly at 87 and 88, so as to engage the opposite edges of a stamp lying on the table 32. These engaging portions 88 are moved away from each other beyond the edges of the plate 58 when the plate is in engagement with the stamp, this movement being effected preferably by tapered projections 89, which wedge themselves between the lugs 90 formed on the slides 86, this wedging action taking place when the plate 58 moves relatively to the head 61 after the engagement of the plate 58 with the receiving table 32. As the head 61 moves upwardly, it frees the slides 86 and permits the hooks 87 to move toward each other under the action of springs 91, which preferably are in the form of leaves bearing at their ends against the projections 90 and supported between their ends by plates 92 secured in recesses in the slides 86. The plates 92 and the slides 86 may be held to the plate 58 by means of securing plates 93, fastened to the guides 60.

To assist the gripping devices, the under face of the plate 58 may be formed with a central pocket 94, from which lead channels 95. This central pocket communicates with a bore 96 in the guide 59 and the upper end of the guide is provided with a tubing 97 which connects with a bore 96. A rubber tubing 98 connects with the tubing 97 and with a suction pump arranged on the base 45 of a machine. This suction pump embodies a cylinder 99 supported on the base and having a piston 100 operating therein, the plunger 101 of this piston being forced outwardly by a spring 102 so that it maintains contact with a cam 103 on a shaft 104. The shaft 104 extends through the cover 25 and is provided at one end with a crank handle 105, so that machine may be operated through the shaft, the latter, for this purpose, having a gear 106 thereon which meshes with a gear 107 formed on the shaft 44.

One end of the cross piece 64 and the guide 62 projects through the opening 108 formed in the casing cover 25 to one side of the table or work support 109, provided on the casing cover, so that it is possible for the stamp carrier and affixer to move to the outside of the casing in order to affix a stamp 65 on an envelop resting upon the support 109.

A brace 109^a is arranged below the table to support the latter. When the head 61 descends toward the work support 109, the plate 58 first engages work and yields to operate the gripping devices 87, in order to free the stamp and permit its application to the envelop.

Any suitable moistening means may be employed. In this instance, a sponge or fibrous material 110 is arranged in a tank 111, between the table 32 and the work support 109, so that the stamp has its adhesive face carried in contact with the moistener, in moving from the table 32 to the work support 109. Liquid may be supplied to the tank 111 by means of a tubing 112 which connects with a supply tank 113 supported within the casing on a standard 114. A plunger valve 115 has a tapered end controlling the outlet 116 of the tank 113 and this valve plunger has an operating portion 117 arranged on the exterior of the casing cover 25.

In Figs. 17 and 18, there has been illustrated a modification of the magazine. According to this modification, a standard 200 is employed secured to the base 6 and having a bearing 201 which receives the bearing 202 on the magazine or rotary carrier. The magazine or rotary carrier has three holders 203 extending radially with reference to the axis of the magazine and each holder embodies two angular arms 203, spaced apart, and having a swinging frame 204 pivoted thereto at 205 and carrying detachable roller 206, on which the roll of stamps is arranged. A spring 207 tends to swing this roller upwardly to the position shown in Fig. 18. The stamps are led from the roll through the guided plate 208 which is pivoted at 209 and carries the pivoted clamping member 210, similar in construction to the clamping member of the other embodiment.

In Figs. 19 and 20, a modification of the stamp carrying and affixing device is shown. This embodiment comprises a head 211 mounted like the head 58, or otherwise, and having a plurality of gripping devices 212 pivoted in pairs at 213 at opposite ends of the head and having ends 214 turned inwardly to engage the stamp on the under face of the head, and ends 215 turned inwardly on the upper face of the head and engaged by spring arms 216 which normally hold the ends 214 to engage a stamp. An abutment 217 simultaneously engages the arms 215 when the plate or head 211 yields relatively to the slide 61 and swings the ends 214 outwardly to release the stamp.

The operation of the invention is as follows: Stamps of the same or different denominations are wound in rolls about the drums 11, the end of the strip being threaded through the opening 16 to lie flat on the guide plate 15, beneath the spring clamp 130

17. One of the guides 15 is alined with the table 32 after which the crank handle may be turned to operate the machine, an envelop having previously been placed upon 5 the work support 109. Starting with the stamp carrying and affixing device arranged above the table 32, the grippers 35 and 36 are in a position shown in Fig. 13. These grippers move to the position shown 10 in Fig. 15 as the stamp affixing device moves to occupy the position shown in Fig. 7. Upon the return of the grippers 35 and 36, a stamp is carried to the table 32 while the stamp affixing device is returned to its position 15 over the table 32 and then descends until the plate 58 contacts with the stamp. A further movement of the head 61 operates the cutter 53 to sever the stamp from its strip and, at the same time, moves the 20 gripping jaw 87, outwardly. On the upward movement of the plate 58, the suction pump operates to suck the stamp against the plate 58 and, at the same time, the grippers 88 engage opposite edges of the stamp 25 so that the stamp is held during the movement of the head 61 to the exterior of the machine. On the downward movement of the head 61 toward the work support 109, the stamp is forced against the envelop as 30 shown in Fig. 7, the plate 58 yielding for this purpose and causing the grippers 88 to release the stamp, the pump at this time also releasing the stamp.

From the foregoing, it will be seen that 35 there has been devised a stamp affixing machine adapted to apply stamps of different denominations with but a slight adjustment of the machine. The different denominations may be readily brought into 40 coöperation with the stamp affixing device, the stamps being positively fed to a stationary table one at a time and severed from the strip after they reach such table. While on the table, they are firmly grasped 45 by the stamp affixing device before being released by the feeder or carrier which places them on the table. The stamp affixing device carries the stamp over a moistening device to the envelop on which the 50 stamp is to be affixed, the stamp being automatically released on such affixing.

What I claim as my invention and desire to secure by Letters Patent is:

1. A stamp affixing machine comprising 55 a receiving member, means for holding a plurality of strips of stamps, separate guides for each strip, the guides being movable to present any one of the strips to the receiving member, means for moving the 60 stamps one at a time to the receiving member, means for severing a stamp from the strip while the latter is on the receiving member, and an affixing device movable to carry the stamps from the receiving member to the envelops.

2. A stamp affixing machine comprising a receiving member, means for holding a plurality of strips of stamps, separate guides for each strip, the guides being movable to present any one of the strips to the receiving member, means for moving the stamps one at a time to the receiving member, means for severing a stamp from the strip while the latter is on the receiving member, an affixing device movable to carry the stamps from the receiving member to the envelops, and a moistening device acting on the stamp while the latter is being carried by the affixing device to the envelop. 75

3. A stamp affixing machine comprising an affixing device, means for holding a plurality of strips of stamps, separate guides for each strip, the guides being movable relatively to the affixing device to present any one of the strips to the affixing device, and a pair of clamping jaws for engaging opposite faces of the strip while the latter is on the guide to move the stamps one at 85 a time to the affixing device.

4. In a stamp affixing machine, a receiving member, means for holding a roll of stamps, a stamp guide leading from said roll to the receiving member, a reciprocating carrier movable to draw the stamps along the guide to the receiving member, 95 including two jaws arranged to clamp the end stamp of the strip between them and an affixing device movable to carry a stamp from the receiving member to the envelop. 100

5. In a stamp affixing machine, an affixing device, a roll holder for the stamps, a guide for directing said stamps from the roll holder to the affixing device, and mounted to turn about an axis situated at right angles to the line of feed, and means for 105 feeding the stamps along the guide to the affixing device.

6. In a stamp affixing machine, an affixing device, a roll holder for the stamps, a means for feeding the stamps from the roll 110 holder to the affixing device, and a pivotally mounted guide for the stamps comprising a plate having a slot through which the stamps are passed to lie in contact with the plate, in their travel to the affixing device, 115 and a movable member holding the stamps to the plate with yielding pressure.

7. In a stamp affixing machine, an affixing device, a roll holder for the stamps, means for feeding the stamps to the affixing 120 device from the roll holder, a pivotally mounted plate having a slot through which the stamps are passed to lie in contact with the plate in their travel to the affixing device, and a spring clamp coöperating with 125 the plate to hold the stamps thereto.

8. In a stamp affixing machine, a receiving table, a roll holder for the stamps, a plate over which the stamps are caused to travel from the roll holder to the receiving 130

table, said plate having a recessed portion, a clamp for holding the stamps to the plate having two spaced arms, reciprocating gripping means movable into the recess of the plate and between the arms of the clamp to pull the stamps onto the receiving table, means for severing the stamps from the strip after they have reached the receiving table, and an affixing device movable to carry the stamps from the receiving member to the envelope.

9. In a stamp affixing machine, an affixing device, a guide for directing stamps to said affixing device, a swinging frame, a stamp carrying roller mounted on the frame, and a spring for moving said roller toward the guide.

10. In a stamp affixing machine, an affixing device, a pivoted guide for directing stamps to said affixing device, a movable roller carrying frame, and a spring for moving said frame to carry the roller to the guide.

11. A stamp affixing machine comprising a drum for supporting a roll of stamps, a movable carrier for such drum, a stamp guide leading from said drum, a table to which the stamps are fed from the guide, a severing device for removing a stamp from the strip while the stamp is on the table, and an affixing device for carrying the stamp from the table to an envelope.

12. A stamp affixing machine comprising a receiving table, a work support, a guide extending from the table to the work support, and movable transversely of its length and a stamp affixer and carrier mounted to reciprocate on said guide.

13. A stamp affixing machine comprising a receiving table, a work support, a guide extending from the table to the work support, and movable transversely of its length a stamp affixer and carrier mounted to reciprocate on said guide, and a parallel link motion for operating said affixer and carrier.

14. A stamp affixing machine comprising a receiving table, a work support, a guide extending from the table to the work support, and movable transversely of its length a stamp affixer and carrier mounted to reciprocate upon said guide, a link pivotally connected to said stamp affixer and carrier, a pair of levers connected for parallel motion, one of said levers being connected to the link, and a rotary driving cam acting on the other lever.

15. A stamp affixing machine comprising a receiving table, a work support, a guide extending from the table to the work support, and movable transversely of its length a stamp affixer and carrier movable on the guide, means for reciprocating the stamp affixer and carrier on the guide, and means for moving the guide transversely of its

length toward the table and work support when the stamp affixer and carrier reaches the ends of its reciprocation in order that the stamp affixer and carrier may be carried toward the table and the work support.

16. A stamp affixing machine comprising a receiving table, a work support arranged substantially in the plane of the table, a guide arranged substantially parallel with the plane of the table and work support and movable toward and from said plane, a stamp affixer and carrier movable on said guide, a rotary cam arranged on that side of the plane of the table opposite that on which the guide is arranged, a pair of levers connected for parallel motion and pivoted on that side of the table on which the cam is arranged, one of said levers being engaged by the cam and the other of said levers extending to the other side of the table, and a link pivotally connected to said lever and to the stamp affixer and carrier.

17. A stamp affixing machine comprising a work support, and a stamp affixer, one of which is movable toward and from the other, the stamp affixer being yieldingly supported and carrying stamp retaining means for engaging opposite sides of a stamp, and a head by which the stamp affixer is carried, having means for operating the stamp retaining means on the stamp affixer on such yielding movement.

18. A stamp affixing machine comprising a work support and a stamp affixer, one of which is movable toward and from the other, the stamp affixer being yieldingly supported and carrying a pair of gripping devices for engagement with opposite edges of the stamp, said gripping devices being controlled by such yielding movement of the stamp affixer.

19. A stamp affixing machine comprising a work support, a stamp affixer, a head on which the stamp affixer is yieldingly mounted, means for moving said head toward and from the support, gripping devices carried by said stamp affixer and engaged by a part on the head when the stamp affixer yields on the head upon co-operation with the work.

20. A stamp affixing machine comprising a work support, a stamp affixer, a head on which the stamp affixer is yieldingly mounted, means for moving said head toward and from the support, a pair of oppositely movable gripping members mounted on the stamp affixer, and a fixed abutment on the head arranged to co-operate with both of the gripping devices to move them from gripping position to release the stamp when the affixer co-operates with the work.

21. A stamp affixing machine comprising a work support, a stamp affixer, a head on which the stamp affixer is yieldingly mounted, means for moving said head to-

ward and from the work, gripping devices arranged on said affixer, springs acting on said gripping devices, and means arranged on the head for coöperating with said gripping devices to move them to release the stamp when the affixer yields on the head.

22. A stamp affixing machine comprising a casing having an offset portion forming a work support, the wall of the casing in 10 proximity to said work support having an opening, a guide movably mounted within the casing and projecting through the opening over the work support, a stamp affixing device movable on the guide into and out 15 of the casing through said opening, and means for feeding stamps to the stamp affixing device while the latter is within the casing.

23. A stamp affixing machine comprising 20 means for supporting a strip of stamps, means for feeding said strip in the direction of its length, a work support, and a stamp affixer and carrier receiving stamps one by one from said strip and movable in 25 a line at right angles to the direction in which the strip is fed in order to carry the stamps to an envelop on the work support.

24. A stamp affixing machine comprising 30 a receiving member, means for feeding a strip of stamps one by one to said receiving member, a cutter movably mounted on said receiving member to cut the stamps from the strip, a spring for moving the cutter away from the strip of stamps, a work support, and a stamp affixer carrying means 35 for engaging said cutter to move the latter to cut the strip as the affixer moves toward the receiving member, said affixer having means for engaging the cut stamp to carry 40 the latter to an envelop on the work support.

25. A stamp affixing machine comprising 45 a work support, a receiving table, a stamp affixer and carrier for moving a stamp from the table to work on the work support, a guide leading to said receiving table, a holder for a roll of stamps arranged to feed stamps to the guide, a gripper arranged to draw stamps from the guide onto the table, 50 and a severing device for cutting a stamp from the strip after it has been fed to the table.

26. In a stamp affixing machine, an affixing device, a receiving member, from which 55 the stamps are taken by the affixing device, a guide for stamps leading to said receiving

member, and reciprocating means for moving the stamps along the guide to the receiving member comprising a reciprocating frame, a stationary gripper jaw supported 60 by said frame, a pivoted gripper jaw also on said frame for coöperating with the stationary gripping jaw, and means for moving the pivoted gripping jaw toward the stationary jaw.

27. In a stamp affixing machine, an affixing device, a receiving member from which the stamps are taken by the affixing device, a guide for the stamps leading to the receiving member, and reciprocating means for 70 moving the stamps along the guide to the receiving member comprising a reciprocating frame, a stationary gripper jaw supported by said frame, a pivoted gripper jaw also on said frame for coöperating with the stationary gripping jaw, and means for moving the pivoted gripping jaw toward the stationary jaw, said means including a pivoted arm having a roller for engaging 75 the pivoted jaw.

28. In a stamp affixing machine, an affixing device, a receiving member from which the stamps are taken by the affixing device, a guide for the stamps leading to the receiving member, and reciprocating means 85 for moving the stamps along the guide to the receiving member comprising a reciprocating frame, a stationary gripper jaw supported by said frame, a pivoted gripper jaw also on said frame for coöperating with the stationary gripping jaw, and means for moving the pivoted gripping jaw toward the stationary jaw, said means including a pivoted arm having a roller for engaging 90 the pivoted jaw, and a rotary cam coöperating with said arm to move the latter to operative position.

29. In a stamp affixing machine, the combination with an affixing device, of a guide 100 for a strip of stamps leading to said device, a pair of grippers, a reciprocating frame on which one of said grippers is pivoted and the other is supported in a stationary manner, a shaft, a spiral cam on said shaft connected to the frame to reciprocate the latter, a cam also mounted on said shaft, and a pivoted lever having a roller for engaging the pivoted gripper and engaged by the cam on the shaft to shift the gripper into co-operation with the stationary gripper.

THOMAS WHALEY.
